US0D1047587S

(12) **United States Design Patent** (10) Patent No.: **US D1,047,587 S**
(45) Date of Patent: ** Oct. 22, 2024

(54) **COMBINED COFFEE MAKER AND COMPONENTS**

(71) Applicant: **SharkNinja Operating LLC**, Needham, MA (US)

(72) Inventor: **Dan Kestenbaum**, Brookline, MA (US)

(73) Assignee: **SharkNinja Operating LLC**, Needham, MA (US)

(**) Term: **15 Years**

(21) Appl. No.: **29/759,680**

(22) Filed: **Nov. 24, 2020**

Related U.S. Application Data

(62) Division of application No. 29/649,477, filed on May 30, 2018, now Pat. No. Des. 906,750.

CLAIM

The ornamental design for combined coffee maker and components, as shown and described.

DESCRIPTION

FIG. 1 is a perspective view of a combined coffee maker and components, showing our new design;

FIG. 2 is a front view thereof;

FIG. 3 is a rear view thereof;

FIG. 4 is side view thereof;

FIG. 5 is another side view thereof;

FIG. 6 is a top view thereof;

FIG. 7 is a bottom view thereof; and,

FIG. 8 is another perspective view thereof.

The broken lines in the drawings depict portions of the combined coffee maker and components that form no part of the claimed design.

1 Claim, 8 Drawing Sheets
